(57) **CLAIM**

The ornamental design for a jewelry element, as shown and described.

DESCRIPTION

FIG. 1 illustrates an upper left perspective view of a chain link showing my new design.

FIG. 2 illustrates a top plan view thereof.

FIG. 3 illustrates a right side elevational view thereof, and the left side elevational view being identical thereto.

FIG. 4 illustrates a front elevational view thereof, and the back elevational view being identical thereto.

FIG. 5 illustrates a right side elevational view thereof in a chain of links.

FIG. 6 illustrates a top plan view thereof in a chain of links; and,

FIG. 7 illustrates a upper side perspective view thereof in a chain of links.

The broken lines in FIGS. 5-7 are environmental and form no part of the claimed design.

1 Claim, 4 Drawing Sheets
